D. D. GORDON

SWITCH

Filed Sept. 19, 1919

Inventor
David D. Gordon
by Jable & Mueller
Atty

UNITED STATES PATENT OFFICE.

DAVID D. GORDON, OF CHICAGO, ILLINOIS, ASSIGNOR TO MCGILL MANUFACTURING COMPANY, OF VALPARAISO, INDIANA, A CORPORATION OF INDIANA.

SWITCH.

Application filed September 19, 1919. Serial No. 324,821.

To all whom it may concern:

Be it known that I, DAVID D. GORDON, a citizen of the United States, residing at Chicago, in the county of Cook and State of Illinois, have invented a certain new and useful Improvement in Switches, of which the following is a full, clear, concise, and exact description, reference being had to the accompanying drawings, forming a part of this specification.

My invention relates to switch mechanisms, and has to do more particularly with the small type of switch ordinarily employed in connection with incandescent lamp sockets, an object being to provide an improved and simplified device of this character.

One of the features of my invention is the provision of an improved yieldingly co-operating set of switch contacts. Another feature is the provision of improved and simplified insulating means for the switch arm.

In the accompanying drawing I have illustrated the preferred form of my invention, in which—

Fig. 1 is a section through the switch shell and switch showing the operating mechanism inside the insulating mounting block;

Fig. 2 is a cross section along the line 2—2 of Fig. 1;

Fig. 3 is a perspective view of the switch arm and yieldingly mounted contact maker carried thereby;

Fig. 4 shows the switch arm in its contact closing position with the contact maker crossing the stationary contact arms; and

Fig. 5 shows another construction for insulatingly supporting the contact arm at the pivot.

Referring now more in detail to the construction shown it comprises a switch mechanism carried inside hollowed insulating mounting blocks 5 and 6 enclosed by a shell 7 and cap 8. A threaded sleeve 9 is carried within the shell for supporting the lamp.

As to the switch mechanism this is in the form of a snap action switch carrying a reciprocatable switch arm operated by a universally mounted switch lever which protrudes from the side of the shell. Referring to the construction shown more in detail it includes a frame 10 secured to the base block 6 and having side arms 11, 12,

each one of which carries an outwardly projecting pivot stud 13 bent out from the frame and on which the switch arm 14 is supported. This switch arm carries a contact maker 15 preferably in the form of a rigid bar extending through a clip 16 the bar 15 resting against a strip 17 of insulating material. The contact bar 15 has a slightly loose fit in the clip 16 so that it may partake of a slight pivotal movement if necessary when engaging contacts 20—21, should they be out of alignment. The clip 16 has an extension 18 projecting through the end wall of the switch arm 14 and attached to an operating spring 19, which serves to throw the switch arm 14 from one position to another and at the same time yieldingly hold the contact maker 15 so that it will give when sliding over the stationary contacts 20, 21. The contact 20 extends through the lower mounting block 6 to the center contact 32 and the switch contact 21 is extended to the binding post 23. The other binding post 24 is connected to the threaded sleeve 9 so that the circuit for the lamp extends from binding post 23 to contact 21, contact maker 15, contact 20, center terminal 32, the lamp, threaded shell 9, to the other binding post 24.

Referring again to the movable switch arm 14 this is preferably insulated from the frame and the rest of the switch mechanism, and to this end I provide bearings 25 which are fork shaped and made of insulating material, the said bearings being slotted to receive the switch arms 14 which are forked at the end and pressed inwardly against the bearings 25. These forked bearings 25 are then slipped over the pivot pins 13 and the arm 14 is held in position by means of the spring 19 which is connected to a floating intermediate link 26 which is in the form of a yoke, the cross piece of which carries a hook 27 to which the spring 19 is secured. The other or free ends of this link 26 have inwardly extending pivot pins 28 which project into holes in the operating link 30. This link 30 is also in the shape of a yoke, the cross head of which carries a connector 31 to which a wire loop 32 is fastened. This loop 32 extends into the operating lever 33 and is held in place by a screw 41. If it is desired to operate the switch by a chain extension, such chain 34 may be held

by the forked ends of the wire loop 32. The lever 33 is supported upon a flanged plate 40, so as to permit a universal tilting movement of the lever 33 and also a lineal movement thereof. That is, this lever 33 may be tilted in any direction or pulled straight out.

Referring back to the intermediate link 26, this carries hook extensions 36, 37, which 10 are adapted to catch over the ends 38, 39 of the frame when the switch is operated by the lever 33. That is, assuming the mechanism is in the position shown in Fig. 1, by operating lever 33, operating link 30 15 is pulled toward the right, thereby acting upon the intermediate link 26 through the pivot 28. Link 26 therefore is first pulled slightly toward the right until the hook 36 engages frame 38 so that a continued movement of the lever 33 imparts a pivotal movement to link 36 about the pivot point 36--38. This continued movement of intermediate link 26 causes its free end to move upwardly and as soon as the point 27 thereof 25 raises the spring 39 so that the moving end passes beyond the center between it and the attached end 18, switch arm 14 moves forwardly by snap action so that the contact maker 15 is freed from the contacts 20, 21. 30 Upon releasing the pressure upon lever 33 spring 19 restores it to its normal position at which time the intermediate link 26 has its hooked end 37 in the lower position for cooperation with the extension 39 on the 35 switch frame. Therefore the next operation of the switch arm 33 will cause an operation of the parts as before, but this time to swing the switch arm 14 downwardly to cause its rigid contact maker 15 to engage and cross 40 the switch contacts 20, 21.

In connection with the switch contacts of devices of this character difficulty is had in securing and maintaining an adjustment of the parts where the flexibility of the stationary contacts, as 20 and 21, is depended upon the effect intimate contact between the switch contacts. To overcome this I have provided the rigid contact maker 15 which is yieldingly carried by the switch arm 14, 45 so that it may yield outwardly or pivotally to properly engage the stationary contacts 20, 21. It is also to be noted that I provide a single spring 19 which acts to operate the switch arm 14 and at the same 50 time permits a yielding operation of the rigid contact member 15 and also holds the forked bearing 25 of the switch arm against the pivot pins 13, thereby securing a most 55 simple and effective structure. By providing the insulated forked bearings 25, the assembling of the switch is simplified as compared with the use of insulating bushings heretofore employed. That is where 60 the insulated bushings are inserted through 65 openings in the sides of the switch arm

14, the assembling of the parts is not so readily accomplished as where the forked bearing is employed.

In Fig. 5 I show another method of insulatingly supporting the switch arm 14 by 70 means of the forked construction and insulated bearing. As shown in Fig. 5 instead of providing a forked insulating member I simply fork the switch arm 14 at 14^a and provide a shouldered bushing 35 which 75 is placed over the studs 13 projected from the switch frame 11. The forked end 14^a of the switch arm 14 is then simply seated against the insulating bearing 35 and the arm 14 held in position by means of the 80 spring 19 and parts 15, 16, and 17 as in the other form already described.

For the purpose of illustrating my device I have shown several constructions but I contemplate employing my invention in 85 other ways than that shown and therefore do not desire to be limited to the construction shown and described but aim to cover all that which comes within the spirit and scope of the appended claims. 90

What I claim as new and desire to secure by United States Letters Patent is:

1. A switch mechanism including a U-shaped switch member, means for pivotally supporting said member at the free ends of 95 its arms, a rigid contact bar mounted upon the yoke of the switch member, a pair of relatively stationary switch contacts for cooperation with the contact bar, and means for yieldingly and pivotally holding the 100 contact bar so that it may pivot and move bodily perpendicularly to the axis of rotation of the switch member.

2. A switch mechanism including a pivotally mounted movable switch arm, a pair of 105 stationary switch contacts, means including a spring for operating a free end of the switch arm toward and away from the switch contacts, and a contact maker supported upon the free end of the switch arm and yieldingly held by said spring so as to be movable independent of the arm 110 for cooperation with the switch contacts so as to operatively engage the contacts.

3. A switch mechanism including an oscillating contact arm having a forked pivotal end, a pivot stud, a contact member and means for yieldingly holding the forked end and stud in cooperative relation and for 115 yieldingly supporting the contact member.

4. A switch mechanism including a U-shaped oscillating contact arm having insulated forked pivotal ends, a pivot stud, and means for yieldingly holding the arm against the pivot but insulated therefrom. 120

5. A switch mechanism including an oscillating contact member comprising a pair of arms having insulated forked pivotal ends and a connecting portion, a pivot stud, and a spring for operating the arm and 130

holding the forked end and pivot stud in cooperative relation.

6. A switch mechanism including an oscillating contact member comprising a pair of arms having insulated forked pivotal ends and a connecting portion, a pivot stud, a contact member, means carrying said contact member extending through said connecting portion, and a spring connected with said means for operating the arm, 10 holding the forked end and pivot stud in cooperative relation and yieldingly supporting said contact member.
- 5 In witness whereof, I hereunto subscribe my name this 13th day of August A D., 15 1919.

DAVID D. GORDON.
